UNITED STATES PATENT OFFICE.

JESSE B. GIBBS, OF SHARON, PENNSYLVANIA, ASSIGNOR TO WESTINGHOUSE ELECTRIC & MANUFACTURING COMPANY, A CORPORATION OF PENNSYLVANIA.

CONSTANT-CURRENT TRANSFORMER.

Application filed September 16, 1926. Serial No. 185,782.

My invention relates to constant-current regulators and particularly to the manner of mounting hinged coils therein.

One object of my invention is to provide a constant-current regulator comprising a hinged coil that shall, regardless of its position, deliver to the secondary circuit a constant current with smaller limits of error than are found in regulators of the types heretofore constructed.

Another object of my invention is to provide a constant-current regulator comprising a hinged coil that shall have means for compensating for differences in the effective turning moment of the moving parts as the position of the moving coil varies from a horizontal plane.

In a constant-current regulating transformer comprising a hinged coil, the force of repulsion exerted on the movable coil by the fixed coil depends on the density of the magnetic field between the coils, on the current in the coils, and on the angular position of the hinged coil. The mechanical force exerted by the counterweight on the hinged coil depends upon the angular position of its lever arm relative to a horizontal plane. The total result of these interacting forces is that a regulator designed in the customary manner will deliver a considerably larger current when its hinged coil is in a horizontal position than when it approaches either end of its travel and is at an angle to the horizontal position.

In the accompanying drawings, Fig. 1 is a view, partially in elevation and partially in section, showing a portion of a regulator embodying my invention when the hinged coil is above its horizontal position.

Fig. 2 is a similar view showing the hinged coil below its horizontal position, and

Fig. 3 is a diagrammatic view showing a characteristic curve of an ordinary constant-current regulator and of a constant-current regulator embodying my invention, with different voltages impressed upon the primary winding and with the secondary winding short-circuited.

My invention comprises, in general, a constant-current regulator 1 having a fixed primary winding 2, a core member 3, and a movable secondary coil 4 that is hingedly mounted on the core member 3, as at 5. The weight of the coil 4 is partially balanced by counterweights 6 and 7 that are mounted on

the lever 8 having a pivot 9. The coil 4 is connected by links 11 and 12 to the lever 8.

A stop 13 is provided on the lever 8 for engaging the link 11 when the coil 4 is above its horizontal position, in order to prevent the link 11 from assuming a position directly in line with the link 12, for a purpose to be hereinafter described.

In constant-current regulators, as heretofore constructed, the small counterweight 7, or some equivalent device, is used to increase the current at the full-load position of the hinged coil, by being oppositely disposed to the counterweight 6 about the pivot 9. If so used, however, it tends to decrease the current while the hinged coil is approaching its top position, as the counterweights 6 and 7 are then disposed on the same side of the pivot 9. The curve GH Fig. 3 shows a typical performance for such regulator which has been adjusted to give the best possible compromise for current adjustment.

By a suitable adjustment of the counterweights 6 and 7, the current delivered by a constant-current regulator, as heretofore constructed, may be made to follow a curve such as MPQ, Fig. 3, instead of the curve GH. The curve MPQ is obtained with the counterweight 7 having a considerable lever arm about the pivot 9. This gives a much better current regulation for heavy loads but a poorer current regulation for light loads.

The operation of the regulator on light loads may be improved by providing the stop 13 for increasing the effective length of the lever arm 8 as it rises, as has been previously described. This action will decrease the external force that tends to lift the hinged coil 4 and, therefore, will cause an increase in the current flowing in the coil, as a greater magnetic repulsive force is then required to separate the coils 2 and 4. The regulation curve will then take the shape MPN, Fig. 3.

As the coil 4 turns about its hinge 5, its effective lever arm about the pivot 9 varies with the position of the lever 8. Referring to Fig. 2, when the coil is in its depressed or full-load position, its effective lever arm about the pivot 9 is represented by line OA and, when the coil is in the horizontal position, this lever arm is represented by the arm OB.

Referring to Fig. 1 and assuming that the stop 13 is not present, the effective lever arm

of the coil 4 about the pivot 9 is represented by the line OC. When the stop 13 is present, the effective lever arm is represented by the line OD. The difference CD is secured by 5 the action of the stop 13 in preventing the link 11 from assuming its natural position in alignment with link 13. As the link 11 is forced out of its normal position, its lower end moves outward away from core 3, there- 10 by increasing the distance between the point of application of the force exerted by the link 12 and the pivot 9. The amount of the difference CD may be determined by the length of the link 11.

15 It is to be observed that the variation in the secondary current of the constant-current regulator embodying my invention, as is shown by the curve MPN, is very much less than the variation in the current of the 20 constant-current regulators heretofore employed, as is shown by the curve GH.

It will thus be seen that I have provided a constant-current regulator in which a stop member is mounted on the lever arm sup- 25 porting the hinged coil to distort the natural position of the connecting link mechanism for the purpose of increasing the effective lever arm of the hinged coil when the latter is above its horizontal position. Accordingly, 30 I am able to utilize a regulator having a smaller departure from its rated current than is possible where the link mechanism connecting the lever and the coil is permitted to assume its natural or vertical position.

35 It is to be understood that my invention may be modified within the spirit and scope of the appended claims.

I claim as my invention:

1. In a constant-current regulator, a sta- 40 tionary coil, a movable coil having a hinge

mounting at one point, supporting mecha- 45 nism comprising a pivoted lever and connecting links, and means for controlling the angular relation between one of the links and the lever to control the effective length 45 of the lever arm supporting the movable coil.

2. In a constant-current regulator, a sta- 50 tionary coil, a movable coil having a hinged mounting at one point, supporting mecha- 50 nism comprising a pivoted lever and connecting links, and means mounted on the lever for controlling the angular relation between one of the links and the lever to control the effective length of the lever arm 55 supporting the movable coil.

3. In a constant-current regulator, a sta- 60 tionary coil, a movable coil having a hinged mounting at one point, supporting mecha- 60 nism comprising a pivoted lever and connecting links, and a stop member mounted on the lever for controlling the angular relation between the lever and one of the links to control the effective length of the lever arm supporting the movable coil. 65

4. In a constant-current regulator, a sta- 70 tionary coil, a movable coil having a hinged mounting at one point, supporting mecha- 70 nism comprising a pivoted lever and connecting links occupying a normal straight- line position, and a stop member mounted on the lever for moving said connecting links from said position under predetermined conditions, thereby to control the effective length of the lever arm supporting 75 the movable coil.

In testimony whereof, I have hereunto 75 subscribed my name this 4th day of Sep- tember, 1926.

JESSE B. GIBBS.
